WEDDING RING

Nathan Heyman, New York, N. Y., assignor to
 Oscar Heyman & Brothers, Inc., New York,
 N. Y., a corporation of New York

Application February 14, 1935, Serial No. 6,414

1. Claim. (Cl. 63—15)

Many brides desire, for sentimental reasons, to be wedded with a ring in the form of a plain gold band, symbolizing unity, but for reasons having less to do with sentiment than with worldly vanity 5 they desire to wear a jeweled ring, symbolizing those things which jewels have always symbolized. In the past this conflict has been resolved in one of two ways, neither satisfactory: A gold band is used at the ceremony, then subsequently dis- 10 carded and replaced by a platinum ring set with precious stones. This practice has the virtue of simplicity and directness; its vice is that madame is not, in point of fact, wearing her wed- 15 ding ring at all; and to many a matron this is, quite understandably, a disquieting thought. Hence has arisen another practice; that of wear- 20 ing upon the same finger two separate wedding rings, one a plain gold band—the true wedding ring—and one a jeweled band worn side by side 25 with that other. This resolution of the difficulty, satisfying at once both sentiment and vanity, does, however, rather crowd the finger and may, perhaps, be criticized as involving too much of a 30 good thing.

25 A truly unhappy dilemma for the proud but punctilious bride—a dilemma now happily resolved by my invention which permits the use of a plain gold band at the ceremony and after, thus satisfying sentiment, and permits the use of a 35 jeweled band too, thus satisfying vanity; all without clumsy duplication. For, in accordance with my invention the gold band is worn simultaneously with the jeweled one, though completely masked thereby. Thus madame continues faithfully and 40 factually to wear the plain gold band which cemented her vows on her wedding day; while at the same time this gold band, significant but un- adorned, is neatly concealed by the jeweled one which alone is visible to the naked and critical eye of the world. And so while in truth wearing 45 two wedding rings, milady appears to be wearing but one.

In attaining the results just described I cut an 45 annular rabbet in an inner edge of the jeweled band and slightly undercut the cylindrical wall thereof, thus forming a groove into which the gold band may be removably seated and inconspic- 50 ously held.

I have illustrated the composite wedding ring 50 of my invention in the accompanying drawing in

which Figure 1 is a plan of the gold band; Figure 2 is a similar view of the jeweled band showing the annular rabbet in which the gold band is seated when the two parts of the ring are assembled; Figure 3 is a transverse section through the center of the assembled ring and showing just how the gold band is seated within the rabbet of the jeweled band; and Figure 4 is a plan of the assembled ring.

In the drawing, 1 indicates the plain endless gold band, the wedding ring used at the ceremony. The precise depth and cross-section of this ring are matters of design and may be varied. It should, however, be a relatively light-weight ring in order that it may conveniently nest within the jeweled band. This jeweled band as illustrated in Figures 2, 3 and 4, and indicated by reference numeral 2, will generally be made of platinum set round about with diamonds 3, or other precious stones, as is customary in rings of this type. 20 In accordance with the present invention an annular groove or rabbet 4 is cut along one inner edge of this platinum ring of such depth and width as to receive the band of gold, which is of substantially the same dimensions. In order that 25 this gold band, when seated, may remain reasonably secure against dislodgment, I slightly undercut the cylindrical wall of the rabbet as indicated at 5, so that a slight pressure is requisite to snap the gold band into place. And once in place, 30 there it remains; although it can be removed by gentle prying, should the exigencies of housework or matrimonial misadventure dictate such a course. In the one case the gold band alone would remain on the finger; in the other, the jeweled 35 one. For it will be observed that the effective internal diameter of both bands is substantially the same. Thus each can be worn separately for each alone will fit the same finger.

I claim:

A composite wedding ring comprising a jeweled outer band having an undercut annular rabbet around an inner edge, and a plain gold inner band removably seated within the rabbet, the depth and width of the rabbet being substantially those of the inner band, so that the internal diameter of both bands is substantially the same and the outer effectively covers the peripheral face of the inner.

NATHAN HEYMAN. 50
